UNITED STATES PATENT OFFICE.

BENJAMIN F. MERRITT, OF EAST ORANGE, NEW JERSEY. ASSIGNOR TO WESTERN ELECTRIC COMPANY, INCORPORATED, OF NEW YORK, N. Y., A CORPORATION OF NEW YORK.

TELEGRAPH SYSTEM.

1,384,396.

Specification of Letters Patent. Patented July 12, 1921.

Application filed October 10, 1917. Serial No. 185,715.

To all whom it may concern:

Be it known that I, BENJAMIN F. MERRITT, a citizen of the United States, residing at East Orange, in the county of Essex and State of New Jersey, have invented certain new and useful Improvements in Telegraph Systems, of which the following is a full, clear, concise, and exact description.

This invention relates to telegraph systems and more particularly to systems for handling multiple distribution of messages from a common or central station to a plurality of outlying stations.

The principal object of this invention is to provide a system for the handling of telegraphic service, wherein messages originating at a main station are to be received simultaneously at a plurality of outlying stations connected by means of line conductors radiating from the main station, the arrangement of the equipment according to this invention being especially applicable to the distribution of news items or other press matter in connection with newspaper work or the publication of periodical literature.

In general this system provides several different methods whereby signaling and communication operations may be carried on between the main station and the outlying stations all in a manner to render one method of signaling independent and non-interfering with other ones of the methods of signaling. This system also provides that the main station may signal or communicate either selectively with a single one of the outlying stations, selectively with more than one of the outlying stations, or collectively to all of the outlying stations simultaneously.

In order that the advantages of the present system may be more readily understood the more important service features desirable in a system of this character will first be briefly considered. In connection with the regular transmission of press matter, say, from a telegraphic bureau to a number of newspaper offices, it frequently transpires that important news items are received at the telegraph bureau from which point such items should be immediately transmitted to the newspaper offices in precedence of less important press matter. In the handling of press traffic such important items are commonly referred to as "flashes". Since a sys-

tem of printing telegraph has proven to be 55 the most satisfactory method for the handling of press service it is important that suitable call signals at the outlying stations be operated by the central station attendant immediately preceding or coincident with 60 the transmission of the more important news items, for which transmission of the less important press matter would of course be interrupted. Such call signaling insures that the special items will receive the immediate attention of attendants at the newspaper offices.

A further service feature relates to the necessity for repeating any portion of a message which may not be properly reproduced at perhaps one or more stations, all as well understood by those skilled in the art. In meeting this requirement the present system provides that from each outlying station an individual signal corresponding therewith may be operated at the main station. Accordingly, on receiving such signal from one or more of the outlying stations the main station attendant may select only such stations as may have signaled and after communicating with them and repeating any portion of a message or furnishing any other information which may have been requested the attendant again establishes connection to resume sending simultaneously or collectively to all of the outlying stations.

In carrying out the present invention a preferred arrangement is based on the employment of equipment to permit simultaneous telegraph and telephone services over each of several circuits which may radiate from a main station to outlying or sub-stations. Telephone conversations and the necessary operation of call signals in connection therewith being carried on over a metallic loop or pair of conductors while the telegraph operations are worked simplex over such line pairs. The present invention also contemplates a modified arrangement to 95 permit the telephone service to be dispensed with although retaining or providing a system of call signals similar to a portion of that employed with the telephone service. It is, of course, well understood in the art 100 that satisfactory telephone service requires each circuit to be formed of a suitably balanced line pair on which the insulation and

the general condition of the construction must be maintained at a relatively high standard, in order to prevent objectionable noises from induction, etc., in the telephone 5 receivers. The alternate arrangement which does not include telephone service would therefore be of particular advantage in situations where the metallic loops may not be formed of line pairs and whereon the insulation 10 and general condition of the lines are not maintained at a standard sufficiently high for telephone service although the telegraphic and call signal working thereover may be entirely satisfactory. Features common, however, to either arrangement relate to individual switching means to selectively connect to any of a plurality of circuits for either call signal or telegraphic operation, and master switching means for collectively grouping all circuits to permit simultaneous operation of either call signals or telegraphic transmission thereover. In connection with such switching, compensating devices are automatically controlled to maintain 25 a constant or uniform current potential of the call signal and telegraphic currents on the line conductors irrespective of the number of lines on which signaling or telegraphing may be under way at any given 30 time.

This invention is illustrated diagrammatically in the accompanying drawings in which only so much of a telegraphic, telephonic and call signal equipment is shown as 35 will be necessary to a clear understanding of the system.

Referring to the drawing, Figure 1 illustrates an arrangement in which telephone and telegraph working and call signal operation 40 may be carried out. In Fig. 2 is shown an alternate arrangement which provides for telegraph working and the operation of call signals.

The equipment shown in each figure of 45 the drawing may be considered as present at a main telegraph station and referring first to Fig. 1, a metallic circuit A formed of a pair of line conductors 10 and 11 will be understood as extending to a distant outlying station (not shown). These line conductors are joined through adjustable rheostats 12 and 13 and windings 15 and 16 of a repeating coil or transformer 14. Through 50 translation effect in the repeating coil, current changes in the windings 15 and 16 when cumulative, one coil with the other, set up corresponding current changes in the windings 17 and 18 and vice versa. Therefore, 55 assuming that the distant station is provided with an alternating current magneto-generator 60 suitable for signaling and a telephone set for talking service, operation of the generator across the line conductors 10 and 11 will set up current action in the repeating coil 14 65 whereby induced currents in windings 17

and 18 thereof complete circuit over the normal contacts 21 of a ringing key 20, normal contacts 27 of a ringing control relay 26, a condenser 31, the winding of a drop signal 32 and the normal contacts 28 and 22 of the 70 relay 26 and key 20, respectively. The drop 32 thereby operated closes its contacts 33 establishing a current source 34 to operate a signal 35. In response to such a call an attendant moves a double pole two-way switch 75 37 to establish its contacts 38 and 39, thereby extending a bridged connection from the leads at the contacts 27 and 28 of the relay 26 to include the windings 17 and 18 of the repeating coil 14 with talking bus conductors 80 7 and 8, which extend to a telephone set (not shown) but labeled at the left-hand side in the drawing. A telephone conversation may now be carried on with the distant station on the line A. When the main station 85 desires to call the station on the line A individually for telephone service, the ringing key 20 is operated, thereby separating its normal contacts 21 and 22 to disconnect the drop 24 and the telephone buses and to 90 close its contacts 23 and 24, thereby connecting a ringing current generator 36 with the repeating coil windings 17 and 18. Translation of these currents through the repeating coil 14 cumulatively energizes the 95 conductors 10 and 11 of line A and operates a suitable call signal which may be assumed as present at the distant station. On this call being answered a telephone conversation may be carried on between the main station 100 and the outlying station as already described. By throwing the telephone switch 37 to the opposite position its contacts 40 and 41 connect the line A with telephone buses 105 5 and 6 which extend to a second telephone set (not shown) as labeled at the right-hand side in the drawing.

A second line circuit B which may be considered as extending to a second outlying station is equipped in a manner identical 110 with the line A. A talking key 52 corresponding with the talking key 37 serves for connecting the line circuit B to either the telephone bus conductors 5 and 6 of one telephone set, or to the bus conductors 7 and 8 115 extending to the other telephone set.

When it is desired to send a call signal from the main station to both of the outlying stations simultaneously, a switch 53, preferably arranged to be operated as a knee 120 or foot switch, is closed, thereby connecting a source of current 54 by way of the bus conductor 4 and the contacts 44 of the switch 42 through the winding of the ringing relay 26. This relay thereby operated separates its contacts 27 and 28 to disconnect the drop signal 32 and the telephone conductors extending to the key 37 and closing of the relay contacts 29 and 30 establish connection 125 from the generator 36 through the repeating 130

coil 14 to operate a signal at the distant station on the line A, as already described in connection with the ringing key 20. Coincident with the energization of the relay 26, 5 current from the bus conductor 4 branches through the contacts 49 of the switch 47 to the winding of the ringing relay associated with the line B, thereby effecting operation of this relay to impress ringing current from 10 the generator 36 over the line B to operate a signal at the distant station thereon, all in a manner similar to the operations described for signaling over the line A.

Referring to the telegraphic portion of 15 the system, for simplexing of the line A a connection branching from a point 19 intermediate the windings 15 and 16 of the repeating coil 14 extends through the normal contacts 43 of the switching key 42, the bus 20 conductor 3, a surge reducing coil 55, the contacts 57 of a switch 56 and an impedance coil 59 to a telegraph transmitter 60, which for convenience has been shown as a manually operated telegraph key, but which may 25 be a keyboard printing telegraph set. Assuming that a suitable telegraph equipment is connected in simplex relation with the line A at the outlying station, operation of the transmitter 60 will set up differential 30 current action in the windings 15 and 16 of the repeating coil 14 and in the line conductors 10 and 11 in a manner to render these currents neutralized or non-effective in the call signal and telephone devices, although 35 such currents will be effective to recompose the impulses into a message record at the distant station, all as well understood in the art. The transfer switch 56 provides that the telegraph bus conductor 3 may be disconnected 40 from the telegraph instrument 60 and connected to a second telegraph equipment comprising a rotary distributor 61 and a group of transmitter contacts 62, which may be considered as tape controlled, and 45 receiving equipment (not shown) may also be considered as included with the distributor. It will be noted that the telegraph bus conductor 3 extends through the contacts 48 of the switch 47 to the neutral or differential point intermediate the two line side coils of the repeating coil associated with the line B, thereby establishing telegraphic service over the line B in simplex arrangement in a manner similar to that already 50 described in connection with the line A.

In case it is desired to send telegraphically from the main station individually, say, to the station on line A, the switch 47 is operated to separate its contacts 48, thereby 55 disconnecting the telegraph bus 3 from the line B and connecting it over the contacts 50 through a compensating resistance 51 to earth. The resistance 51 is calibrated or proportioned to be equal to the joint resist-

ance of the two line conductor paths which form the line B as routed through the telegraph equipment to earth at the distant station. It will, therefore, be clear that on sending from the telegraphic equipment at the main station the impulses will only 65 traverse the line A in parallel with the compensating or artificial resistance 51. The telegraphic impulses therefore will have the same potential or current resistance drop at the bus conductor 3 and on the line A as 70 present when the line B is grouped therewith, instead of the resistance or artificial line 51.

It may be mentioned that operation of the switch 47 by separation of its contacts 49 disconnects the ringing relay of the line B. Therefore, in case the foot switch 53 is operated during the time the switch 47 stands 80 operated, call signal current will only be transmitted out over the line A or any additional lines (not shown) which may be grouped with the latter line.

When it is desired to send or communicate telegraphically only with the station on line B, the switch 42 is operated, separating its contacts 43 to disconnect the telegraph bus conductor 3 from the line A, and through the closing of the contacts 45 to connect this bus through a compensating resistance 46 to earth, the resistance 46 being equal to the 90 resistance of the telegraph circuit as simplex over the line A.

The purpose of the adjustable resistances 12 and 13 in the line A and the corresponding resistances in the line B is to permit uniform balancing of the circuits irrespective of any difference in the size or gage of the line conductors, or any difference in the length of the line circuits as compared one with another. To make this point clear let it be assumed that the telegraphic devices are proportioned or adjusted to standards whereby with line batteries of predetermined potential the most satisfactory working will be had when the actual resistance 100 of the line circuit conductors to each station is, say, 1000 ohms. Therefore, this resistance value for a simplex circuit means that the loop resistance of the two line conductors would be 4000 ohms. Assuming 110 that the loop resistance of the line A is equal to 1600 ohms, each one of the resistances 12 and 13 would require to be adjusted to represent a resistance of 200 ohms, and assuming that the loop resistance of the line B to be 1000 ohms the calibrating resistance therein would require to be set to represent 115 500 ohms each. It will be clear that by this method of calibrating through adjusting the resistance in each line conductor of each circuit, a symmetrical branching or distribution of call signal currents, telephonic currents and telegraphic currents is effect-

120

125

ed in multiple operation from the central station between a plurality of lines extending to several outlying stations.

Referring to Fig. 2 of the drawing the general layout of the arrangement shown therein has, for convenience of description, been made similar to that shown in Fig. 1 and, where possible, like characters of reference have been employed in designating like parts. In order to simplify the drawing, the equipment for sending out call signal currents from the main station has not been shown, but it will be understood that, if desired, equipment similar to that shown in Fig. 1 may be employed for such service.

In tracing an incoming call from the outlying station on the line A it will be understood that suitable ringing current would be applied to the line conductors 10 and 11 at the distant station. Such currents translated through the repeating coil 14 complete circuit through the uppermost winding of a signal control relay 64. This relay thereby initially operated establishes a self-locking circuit which may be traced from a source of current 75, the contacts 71 of an answering key 70, contacts 66 and the lowermost winding of the relay 64 and the winding of an auxiliary signal relay 76 to earth.

The contacts 65 of the relay 64 include a source of current 67 to light a lamp signal 68. The relay 76 also operated establishes a source of current 77 to operate an auxiliary signal 78. In the absence of telephone instruments this call would be answered by means of the telegraph, to accomplish which the key 70 is operated, whereby separation of its contacts 71 disconnects the locked relay 64, which in turn disconnects the lamp 68 and the auxiliary relay 76, whereby the signal 78 is disconnected. Closing of the contacts 73 of the key 70 connects the source of current 75 through the winding of a relay 84 in series with the winding of a relay 86, thence over the contacts 92 of a transfer key 90 to earth, thereby operating both of these relays. Separation of the contacts 72 of the key 70 disconnects the telegraph lead of the line A from a bus conductor 81 and connects it to a bus conductor 82. Separation of the contacts 85 of the relay 84 severs a tie connection whereby the bus conductor 81 is normally joined with the bus conductor 82, and separation of the contacts 87 of the relay 86 removes a shunt from around a resistance unit 89. These circuit changes disconnect the telegraph lead from the line B and establish a connection with the line A which may be traced from a telegraph equipment 100 over an impedance coil 101, a switch 102, the resistance unit 89, the contacts 93 of the transfer key 90, the bus conductor 82, the contacts 74 of the key 70, an adjustable resistance 121 to the differential or simplex point 19 of the line A.

It will be understood that suitable receiving equipment is included with the transmitting set 100, whereby telegraphic communication may now be carried on individually from the main station to the distant station on the line A. In the present arrangement the line calibrating resistance comprises a single unit for each line and is inserted in the telegraph lead as the resistance 121, which permits adjustments for establishing a uniform resistance for each of the several telegraph circuits in effect the same as already described in connection with Fig. 1. This arrangement is permissible since the more important multiple sending from the main station is over the simplex telegraph circuit, the call signal operations coming in individually from outlying stations as described. In setting up the switching operations to individually select and answer the station A, as just set forth, the compensating unit 89 is effective serially with the telegraph lead to establish the same potential of the telegraph currents on the single line A as were present when this line was grouped with the line B. This may be made clear by assuming as an example that ten different lines similar to the lines A and B, and calibrated to a resistance of 1000 ohms each, are grouped for multiple transmission from the central station, at which point the potential of the line current supply is 100 volts and the series resistance of the protective devices, impedance unit, etc., make a total of 25 ohms. Since the joint resistance of the ten 1000-ohm lines would equal 100 ohms, the potential drop around the 25 ohms would be 20 volts, while the drop around the joint 100 ohms of the lines would be 80 volts. The common bus conductor from which each line circuit branches would, therefore, have a potential of 80 volts under telegraphic currents. Assuming now that in case a single line is selected from such a group of ten lines the series resistance, as the resistance 89, in order to maintain the common telegraph bus conductor at 80 volts would represent a resistance of 225 ohms. This will be apparent from the proportion that the 80-volt line drop would be to the single 1000-ohm line as 20 volts would be to 250 ohms, and since the telegraphic devices at the central station have a resistance of 25 ohms, as already assumed, such twenty-five ohms would be subtracted from the total of 250 ohms which would give 225 ohms as the value for the resistance 89.

In the operation of this system it is desirable at times to disconnect, perhaps, only one or a few stations from a multiple group and for this purpose a key switch and a compensating resistance is provided for each line. A key 103 and resistance 106 are arranged to render this service in connection with the line A, while a key 107 and the

associated resistance effect corresponding service for the line B. To disengage or disconnect the line A the key 103 is operated, separating its contacts 104 to disconnect the line A from the bus conductor 81 to which it is normally connected through the contacts 72 of the answering key 70. Closing of the contacts 105 of the key 103 connects the bus conductor 81 through the compensating unit 106 which has a resistance value equal to that of the simplex line A, and the calibrating resistance 102. Assuming now that transmission is progressing from the telegraph instrument 100, the relays 84 and 86 and the key 70 being restored to their normal positions, while only the key 103 stands operated, impulses pass from this transmitter through the impedance coil 101, the switch 102, the contacts 87 of the relay 86, the contacts 93 of the transfer key 90, thence to the bus conductor 82, first branching through the contacts 85 of the relay 84, to the bus conductor 81. From the latter bus these impulses branch, a portion of the current traversing the contacts 105 of the key 103 and the resistance 106 to earth, while the remainder traverse the contacts 108 of the key 107, the contacts 111 of the key 110, thence over a calibrating resistance 115 to the line B. It will be noted that the bus conductor 82 is ineffective at this time since it stands open-circuited at the contacts 74 of the key 70 and at the contacts 113 of the key 111. For group or multiple service let it now be assumed that the key 103 is restored to its normal position whereby the resistance unit 106 is disconnected and the bus conductor 81 is established over the contacts 104 of the key 103 and the contacts 72 of the key 70 with the line A. In transmitting from the instrument 100 the telegraphic impulses reach the bus conductor 81, whence the currents branch equally over the lines A and B over the paths already traced.

It will be understood that the telegraph set 100 would preferably be arranged as a keyboard telegraph set located on a telegraph table which also carries a tape controlled or automatic telegraph set 116 and that a second telegraph table contains the sets 118 and 120, which are in duplicate of the sets 100 and 116 respectively. The transfer key 90 is for the purpose of transferring the telegraph service from one table to the other. In describing this transfer feature of the system it will be pointed out that the three relays 84, 86 and 119 are connected in series, but due to the key 90 only two of the relays may be operated at one time. In the position shown the contacts 92 of this key established a short circuit around the winding of the relay 119, leaving the relays 84 and 86 responsive to either of the answering keys 70 or 110. When the key 90 is in the normal position its contacts 91 establish a short circuit around the winding of the relay 86, thereby rendering the relays 84 and 119 responsive to the answering keys. The transfer key also conditions circuits to permit local testing of the telegraph equipments on an idle table. When positioned as shown in the drawing the sets 100 and 116 on the left-hand table are connected for service over the circuits already traced, while local test circuits from the right-hand table may be traced from the tape controlled set 120 over the associated impedance coil, switch, and right-hand contacts of the relay 119, the contacts 94 of the key 90, thence through a resistance unit 97 which is calibrated to represent a resistance value equal to a group of multiplied line circuits corresponding with the lines A and B. A second position of the key 90 separates its contacts 93 and 94 and closes its contacts 95 and 96, the contacts 91 also being closed while the contacts 92 are open. Either one of the telegraph sets 118 or 120 now becomes effective for service over the contacts 96 of the key 90, while either of the idle sets 100 or 116 may be tested locally over a circuit through the contacts 95 of the key 90 and the resistance unit 97. On answering an individual call from the right-hand table, operation of the answering key, as keys 70 and 110, causes the operation of the relays 84 and 119. Operation of the latter relay removes a short circuit from around the series compensating resistance associated with these telegraph sets in order to regulate the potential of the telegraph currents on the single line answered as already described in connection with the set 100. At each table the switches corresponding with the switch 102 for the set 100 serve to cut the associated set in or out of circuit, it being understood that only one set on each table may be in use at one time, either for line service or for local testing, depending on the position of the transfer key 90. The purpose of the condensers, one legged to earth from each telegraph set, is for absorbing surges of current set up by the telegraph operations.

In reference to the capacity of the system, any number of branching lines may be added thereto by providing individual equipment for each line, as illustrated and described in connection with the lines A and B. For the arrangement shown in Fig. 1 of the drawing such individual equipment would interconnect from an added line to the bus conductors 1 to 8 inclusive, while for the arrangement shown in Fig. 2, the equipment for each additional line would interconnect to the bus conductors 80 to 83 inclusive in a manner similar to the connections for the equipments illustrated.

What is claimed is:

1. In a signaling system of simultaneous

- telegraphy and telephony, a plurality of line circuits, a central station and outlying stations connected by said line circuits, means for telegraphing over said line circuits, switching means for either selectively or collectively engaging said lines for telegraphing thereover, and resistances controlled by said switching means and substituted thereby for non-engaged lines.
- 10 2. The combination of a plurality of line circuits extending from one station, of apparatus at said stations for telegraphing over said lines, of means at said station for receiving call signals over said lines simultaneously with said telegraphing, switching means for either selectively or collectively engaging said lines for use, artificial lines and means controlled by said switching means for substituting one of said artificial lines for each non-engaged one of said lines.
- 15 3. In a system of simultaneous telegraphy and telephony, a main station, a plurality of outlying stations, line circuits extending from said main station to said outlying stations, means for either selectively or collectively engaging said lines for communication from said main station, and means for maintaining uniform current consumption telegraphically on each engaged line irrespective of the number of lines under communication.
- 20 4. A system for permitting the simultaneous operation of both telegraphic and telephonic equipment comprising a central station, outlying stations, lines for connecting said outlying and said central stations, a resistance, means for simultaneously transmit-
- ting telegraphic signals over said lines from said central station to said outlying stations, and means for rendering either of said lines unaffected by said telegraphic signals and for substituting said resistance for said unaffected line.
- 25 5. In a telegraph distributing system, a plurality of line circuits, switching means for either selectively or collectively engaging said lines, means for telegraphing over said lines as selectively or collectively engaged, means for telephoning over said lines as selectively or collectively engaged simultaneously with said telegraphing, call signals for said lines, and means for operating said call signals over said lines as selectively or collectively engaged simultaneously with said telegraphing.
- 30 6. The combination of a plurality of line circuits extending from one station, of apparatus at said station for telegraphing over said lines, equipment at said station for telephoning over said lines simultaneously with said telegraphing, equipment at said station for transmitting call signal operating currents over said lines simultaneously with said telegraphing, means for calibrating the resistance of each of said lines to a predetermined value, switching means for either selectively or collectively engaging said lines for use, a plurality of artificial lines, and means controlled by said switching means to substitute an artificial line for each line which may be non-engaged.

In witness whereof, I hereunto subscribe my name this 5th day of October A. D., 1917.

BENJAMIN F. MERRITT.
